UNITED STATES PATENT OFFICE.

BENJAMIN H. ALVEY, OF LOUISVILLE, KENTUCKY.

AUTOMOBILE-TOP.

1,251,731.

Specification of Letters Patent. Patented Jan. 1, 1918.

Application filed March 24, 1916. Serial No. 86,414.

To all whom it may concern:

Be it known that I, BENJAMIN H. ALVEY, a citizen of the United States, residing at Louisville, in the county of Jefferson and State of Kentucky, have invented certain new and useful Improvements in Automobile-Tops, of which the following is a specification.

This invention relates to vehicle tops, and particularly to tops for automobiles of the style commonly known as inclosed or winter cars, and consists in certain peculiarities in the construction and arrangement of parts and in certain novel combinations of elements substantially as hereinafter described and particularly pointed out in the subjoined claims.

The principal or ultimate object of the invention is to provide a top of the style stated which will afford adequate protection against cold and damp weather and present an appearance substantially equal to that of the best styles and grades of glass inclosed tops, and at the same time will be much less expensive and more durable, and much more easily opened up to afford circulation of air therethrough, when desired.

Another of the important objects of the invention is to provide, in a top having curtains arranged to be raised or lowered to open or close the car to or against the atmosphere, means of most practicable nature for guiding the curtains in their movement between their open and closed positions, the said means being of such nature as to cause the curtains to move smoothly and easily and avoid all danger or possibility of creasing, binding or pinching of the curtains at any place.

These important objects, and others which will be apparent to those persons who are familiar with the present invention, are best secured from the construction and arrangement of parts illustrated in the accompanying drawings and hereinafter described in detail, but I would have it understood that this construction and arrangement of parts is merely exemplary and that changes may be made in the details and that the invention may be otherwise and variously embodied without departing from its spirit or the scope of the subjoined claims.

In the accompanying drawings, wherein

like characters of reference denote corresponding parts in the several views: 55

Figure 1 is a longitudinal section on the line 1—1 of Fig. 3.

Fig. 2 is a plan view with the top covering and upper strips removed.

Fig. 3 is a transverse section on the line 3—3 of Fig. 1, looking toward the front of the car.

Fig. 4 is a longitudinal section through the back curtain, on the line 4—4 of Fig. 1.

Fig. 5 is a detail sectional view of one end 65 of one of the forward side curtains and a part of the wind shield on the line 5—5 of Fig. 3, showing the connection of the front end of said curtain and the wind shield.

Fig. 6 is a detail sectional view on the line 70 6—6 of Fig. 7.

Fig. 7 is a detail view, in elevation, showing the lower end of one of the transverse bows, with anti-friction rollers, a part of the rail and a standard, together with means 75 for connecting the rail to the upper end of the standard.

Fig. 8 is a transverse section through the standard shown in Fig. 7, on the line 8—8 of Fig. 7. 80

Fig. 9 is a detail view, showing the lower part of a standard in elevation, and also showing the adjacent portion of the body in section, this view illustrating the manner of connecting the standard to the body. 85

Fig. 10 is a view, partly in elevation and partly in section, illustrating the connection of a standard to the body when viewed at right angles to Fig. 9 and also illustrating the lower end of side curtains in the standard. 90

Fig. 11 is a detail view showing the stiffened lower end of a curtain on longitudinal section, with a hand hold thereon.

Fig. 12 is a perspective view of an automobile provided with my improved top.

A designates the body of the vehicle and B the top considered as a whole. This top is of rigid or non-folding type. It is provided at each side with curtains marked b, b' and 100 b² respectively and at the back with a curtain marked b¹.

These curtains are so arranged that the top may be closed in or partly or completely opened at the sides and back, to suit varying 105 weather conditions.

The frame of the top may be of any suitable construction. The one herein disclosed is formed of a rail 1 which extends along each side and across the front; a series of 5 transverse bows 2 which are suitably spaced and have their downwardly curved ends secured to the rail 1; a second series of transverse bows 3, arranged below the bows 2 and vertically aligned with the latter and 10 having their ends secured thereto, a series of longitudinal strips 4 which are secured to the outer surfaces of the bows 2 and connect the latter, and inner side strips 1^a arranged below the ends of the bows 3 and in line with 15 the longitudinal members of the rail 1. It is considered to be unnecessary to illustrate the fastening of the frame elements to each other as it is wholly immaterial what means of suitable character are employed for the 20 purpose.

6 designates the outer or top covering, which may be of leather, pantasote or other suitable material, and 7 designates an inner lining of any suitable material. Between 25 this covering and lining a space is afforded which receives the curtains when the latter are raised. Journaled in this space and extending longitudinally of the top are two series of rollers 8 for the side curtains—one 30 roller for each curtain—and a transversely arranged roller 9 for the rear curtain. In practice the rollers 8 for the curtains on the right of the car are arranged at the left side of the top and the rollers 8 for the curtains on the left side of the car are arranged at the right side of the top, as shown in Fig. 3. The rollers 8 and 9 may be of any suitable kind, spring rollers of approved construction being preferred.

40 Each side of the top comprises suitable standards marked 10, 10 and 11. The standards 10, 10 are preferably formed as shown in Fig. 8. This form of standard is made of sheet metal, hollow, and stamped to provide longitudinal channels 12 in its opposite sides. Each standard 11 may be of similar construction except that only one of its longitudinal sides is formed with a channel. The standards, as best shown in Figs. 7 and 50 3, have their upper ends secured to the rail 1 by brackets 13.

Each of the standards 10, 10 and 11 has its lower end resting upon the upper edge of the body and secured thereto in any approved way, the securing means being preferably concealed. I have devised an advantageous way of connecting the standards to the body as follows:—Each standard has at its base a flange 14 from which extends a hook 15. This hook enters a pocket 16 formed in the contiguous part of the body and within this pocket there is a suitable element to be engaged by the hook. When the body is formed, as is common, of an outer

sheet of metal, a, stiffened by a wooden back-⁶⁵ ing, as a', the latter is preferably formed at appropriate places with recesses which form the pockets 16 and with grooves 17 which extend from the recesses, and metal strips 18 are arranged in the grooves so as to be held by the walls thereof, the said strips having their upper ends in the pocket 16 and formed with apertures 19 which receive the hooks 15, the latter engaging the upper walls of the apertures: all as clearly shown ⁷⁰ in Figs. 9 and 10.

The edges of the side curtains are reinforced, by cords, or other suitable elements 20, and the grooves or channels 12 formed in the standards 10, 10 and 11 are shaped to receive said edges and to permit the latter to travel therein without danger of lateral displacement therefrom.

The lower ends of the bows 2 rest on the upper ends of the standards and are provided with elements which form, in substance, arcuate passages arranged to have communication with the channels 12 and within which the reinforced edges of the curtains travel between the vertical position ⁸⁵ 90 which they occupy when the curtains are closed and the horizontal position they occupy when open. The elements referred to as forming the arcuate passages are series of spaced rollers 21, preferably of a grooved ⁹⁵ nature to prevent displacement of the reinforced edges of the curtains therefrom, the said rollers being freely rotatable on horizontal axes. There are two series of these rollers spaced along each bent portion of ¹⁰⁰ each bow 2, the rollers of the two series being relatively so arranged as to form opposite freely rotatable walls of an arcuate passage which guides the adjacent edge of the curtain around the bend. The preferred ¹⁰⁵ form is illustrated best in Fig. 6, upon reference to which it will be noted that the idlers are formed of outwardly tapered bodies having flanged outer ends, the flanges being marked 21^a, the two complementary ¹¹⁰ series thus forming an inwardly narrowed passageway with rotatable walls and a restricted mouth. The idlers are mounted on stub shafts or pivots 22 and the several stub shafts or pivots of the idlers forming a passageway are preferably mounted on a common ¹¹⁵ plate 23 which is longitudinally curved to conform to the portion of the bow to which it is secured. These plates are secured to the bent portions of the bows by any suitable means. It will, therefore, be seen that the comparatively short rollers 21 lying in spaced relation present laterally open passageways which open toward the curtain openings to which they are related to thereby adapt them to serve as guideways for their respective curtains. Similar guiding means are provided for conducting the back ¹²⁰ ¹²⁵

curtains b^3 around the bends. The latter guiding means comprising two complementary series of idlers, marked 21^b for each lateral edge of the curtain b^3 , these idlers being carried by plates 23^a which respectively are attached to short bent frame members 23^b as will be seen upon reference to Figs. 1 and 2. The lateral edges of the back curtain b^3 below the guiding means last referred to instead of traveling in grooves formed in standards extend into pockets 24 suitably formed in the quarters 6^a of the top, as shown in Fig. 4. Suitable fastenings 31 are provided on the quarters 25 and rear curtain for securing the latter in closed position. These fastenings may be buttons of the type commonly employed for holding automobile curtains in position. For a purpose which will later appear there are no standards provided for the front edges of the forward side curtains b' .

Each of the curtains is made principally of a suitable transparent material 25—celuloid being preferred—there preferably being in practice only sufficient curtaining material 32 to form a proper framing for the transparent material, thereby enhancing the looks of the car and conducting to the comfort of the passengers. Each side curtain b and b^2 is provided, below the transparent material with a strip 26 of approximately rigid material as wood, which reinforces the curtain and serves as a stop to indicate when the curtain is in its lowermost position, being so arranged that it rests upon the upper edge of the body or the upholstery, when the curtain is lowered. The rear curtain b^3 may also, if desired, be provided with a rigid strip like those described 40 with relation to the side curtains.

As is customary in the construction of automobile bodies and tops, the sides of the body A at the front of the car are curved toward each other and the top slopes downward toward the front. For these reasons, and as it is desirable that the forward curtains b' conform to such shape and at the same time be arranged to be fully and easily raised and lowered: the said forward curtains are each provided with two separate sheets of transparent material, the confronting vertical edges of which are secured to a flexible frame strip 30. These frame strips are arranged intermediate the length 55 of the respective curtains b' and substantially in line with the places where the sides of the body curve inward toward each other. Each of these curtains b' has a reinforcing strip 26^a which corresponds to the strips 26 of the other curtains, but which terminates with its forward end substantially in vertical alinement with the frame strip 30, instead of extending entirely across the curtain. The forward portion of the

curtain hence conforms to the shape of the 65 body without danger of breaking the celluloid or transparent material of which it is largely composed. The vertical edges of these forward side curtains b' are provided with strips 21^a which may be suitably secured by appropriate fastening elements 31^a projecting from the frame of the wind shield (as shown in Figs. 3 and 5). These strips 21^a are of substantially the length 75 of the curtains b' and close the spaces between said curtains and the ends of the wind shield.

In order to avoid the necessity of having the curtains themselves run upon the rollers 8 and 9, the upper edges of the curtains are 80 connected with the rollers by flexible sheets of suitable material, as linen, or the like, and so arrange the rollers and the relative lengths of the curtains and strips that the strips only will run upon the rollers, the 85 curtains themselves being never rolled. The strips for all the curtains except those at the front are marked 29. These strips 29 are of substantially the same width as the curtains to which they respectively are secured 90 and hence are adapted to roll smoothly upon the rollers, hence, aid the channels and passages in causing the curtains to move smoothly and freely to a much greater extent than would be possible by spaced cords 95 or the like at opposite edges of the curtains. The rollers 8 for the forward side curtains b' are inclined downwardly from their rear ends, so as to lie in parallelism with the adjacent part of the top B, as 100 shown in Fig. 1. To cause these curtains b' to run smoothly, notwithstanding the hereinbefore referred to shapes of the fronts of the top and body, each of the curtains b' is connected with its roller by two separate 105 strips of material, marked 29^a and 29^b respectively, the strips 29^a being throughout its length of substantially the width of that part of the curtain b' from the rear edge of the latter to the intermediate frame strip 110 30 and the strip 29^b being cut on a bias from its roller 8 to its curtain, as shown in Fig. 2.

Each curtain is provided with hand holds 115 for convenience in raising and lowering it. These hand holds are secured by suitable fastenings which extend into the stiffening strips 26 or 26^a. The curtains are also formed with aprons 28 which extend below the strips 26 and are arranged on the outside of the body and serve to prevent the entrance of air or water into the car from below the curtains.

It is believed that the construction, operation and advantages of the present invention will be fully understood from the foregoing description, and that it will be apparent that while the construction herein

illustrated and set forth in detail is well calculated to carry into practice in a most practicable manner the several purposes in view yet changes may be made without departing from the spirit of the invention defined by the appended claims.

Having now described the invention what I believe to be new and desire to secure by Letters Patent, is:

10. 1. In a vehicle top, a curtain arranged to be raised or lowered, and means forming channels at opposite sides of the curtain openings to receive the longitudinal edges of the curtain, the means forming each of said channels including two series of short rollers relatively disposed to present a laterally open, arcuate passage having rolling walls to engage the adjacent portions of the curtains.
20. 2. In a vehicle top, the combination with standards and bows, the latter having arcuate portions, of a curtain arranged to be raised or lowered, and means for guiding the curtain in an arcuate path while it is being raised or lowered, comprising two sets of stub shafts, having idler rollers thereon, one set being mounted at each side of the curtain opening and upon the side faces of the arcuate portions of the bows, the rollers of each set lying in two concentric rows, and the rollers of one row being spaced from the rollers of the other row to thereby constitute a laterally open passage by which the adjacent portion of the curtain is guided.
30. 3. In a vehicle top, the combination with a series of transverse bows having arcuate portions, of plates secured to the side faces of said arcuate portions, outwardly projecting stub shafts carried by said plates and rollers journaled upon said stub shafts and arranged in spaced relation and in two concentric arcuate rows to constitute between them a passageway which opens laterally with respect to the curtain opening toward which said rollers face.
40. 4. In a vehicle top, a curtain arranged to be raised or lowered and having enlarged longitudinal edge portions, and two series of short freely rotatable rollers at each side of the curtain opening, the rollers of each two series being correlated to provide an arcuate space having a laterally open restricted mouth, the said spaces being disposed to receive the adjacent enlarged longitudinal edge portions of the curtain, and the portions of the curtain contiguous to said edges extending through the mouth, whereby accidental displacement of the curtain is avoided and said curtain is guided in an arcuate path.
50. 5. In a vehicle top, a curtain arranged to be raised or lowered and having reinforced longitudinal edges, and means for guiding the curtain in an arcuate path while the curtain is being raised or lowered, the said means including two series of grooved idler rollers at each side of the curtain, each pair of series of rollers being relatively arranged to form, substantially, an arcuate passage which receives the adjacent reinforced edge of the curtain and has a restricted mouth.
6. In a vehicle top, a curtain arranged to be raised or lowered and having reinforced longitudinal edges, and means for guiding the curtain in an arcuate path while the curtain is being raised or lowered, the said means including arcuate members adjacent to the longitudinal edges of the curtain, each arcuate member having two series of idler rollers mounted to rotate on approximately horizontal axes, each roller comprising an outwardly tapered body having a flange at its outer end, the rollers of each two series being relatively arranged to form, substantially, an arcuate passage having freely rotatable outwardly diverging walls and restricted mouth.
7. In a vehicle top, the combination of standards and bows, the standards having channels, two complementary series of independently rotatable idlers spaced along the curved portion of each bow, each idler having an outwardly tapered body and a flange at its outer end, the idlers of each two series being relatively arranged substantially to provide an arcuate passage, said passages communicating with the channels in the standards, respectively, and a curtain having reinforced longitudinal edges respectively arranged to travel in the grooves of the standards and between the complementary series of idlers, and to be guided thereby.
8. In a vehicle top, a roller extending longitudinally thereof at a downward inclination, a curtain bendable vertically on a line between its ends, and two flexible strips of material connecting opposite end portions of the roller with corresponding portions of the curtain, one of said strips being cut on a bias.
9. In a vehicle top, a roller, a curtain disposed at the juncture of the front and side portions of the vehicle and lying partly along the side and partly across the front and connections whereby said curtain may be wound upon said roller.
10. In a vehicle top, a roller, a curtain disposed at the juncture of the front and side portions of the vehicle and lying partly along the side and partly across the front and connections whereby said curtain may be wound upon said roller, said connections comprising two flexible strips of material connecting opposite end portions of the roller with corresponding portions of the curtain, one of said strips being cut on a bias.
11. The combination of a vehicle body

having an outer covering sheet of metal and a backing member for said sheet, the backing member, having an upwardly open pocket and a groove extending from the 5 pocket, a metallic element arranged in the groove and extending into the pocket, the portion of the element in the pocket having an aperture, a standard mounted on the edge of the body adjacent to the pocket and a

hook extending from the standard into the 10 pocket and having its inner end received by said aperture in the element.

In testimony whereof I affix my signature in the presence of two witnesses.

BENJAMIN H. ALVEY.
